INDICATING DEVICE

Clyde L. Gilbert, Terre Haute, Ind.

Application March 28, 1935, Serial No. 13,490

10 Claims. (Cl. 116—130)

This invention relates to an indicating device.

The chief object of the invention is to construct an indicating device so that it may be readily and manually manipulated by a pencil, 5 fork tine, paring knife or finger nail, to move one of the indicators from non-indicating to indicating position.

Another object of the invention is to provide an indicating device of this general character, 10 which, by a single movement of a single member, will simultaneously return all of the indicators moved to indicating position, into the non-indicating position.

Another object of the invention is to provide 15 a device of this general character which can be economically constructed with a minimum number of parts, with a minimum amount of labor, and with minimum waste.

The chief feature of the invention consists 20 in the accomplishment of the foregoing objects and other incidental features will be set forth more fully hereinafter.

The full nature of the invention will be understood from the accompanying drawing and the 25 following description and claims:

In the drawing, Fig. 1 is a front elevational view of one embodiment of the invention.

Fig. 2 is a sectional view taken on broken line 2—2 of Fig. 1 and in the direction of the arrows.

Fig. 3 is a plan view of the device in extended 30 relation.

Fig. 4 is a sectional view taken at right angles to Fig. 2 and illustrates one of the indicating fingers or pointers in non-indicating position and another one in the indicating position.

Fig. 5 is a view similar to Fig. 1 on a somewhat smaller scale and of a modified form of the 35 invention.

In the drawing, 10 indicates a base and 11 a cover, the two being united by means of the 40 scored connection 12. This is interrupted as at 13 to provide a tab portion 14 which is perforated as at 15, whereby the entire device when the cover is folded over the base, may be hung 45 from a nail or other suitable support. The cover—see Fig. 1—on its two side marginal portions adjacent the elongated aperture 16 therein has printed thereon, preferably in alphabetical relation, a list of articles to be ordered 50 from time to time from the grocer or butcher, et cetera.

Surrounding the aperture 16 is a border 17 which has a contrasting legend forming, as it were, representations of different compartments 55 18, which representations are of greater area

than the ends of the indicators or pointers, so that when an indicator is positioned in exposed overlapping relation relative to the border, the end of the pointer is of contrasting outline, as shown clearly in Fig. 1. This border may be of 5 printed character and may have article designating projecting portions as indicated at 19.

Preferably, the border legending is of dissimilar color to the body or general color and also preferably the indicating figure or pointer 10 is of another contrasting color, so that when the pointer is tripped and passes through the aperture and overlies the cover in the compartment representation, the color contrast between the three elements last mentioned, visually increases 15 the effectiveness of the desired indication. For example, the border may be in black, the body of the cover in yellow, cream or white and the pointer in red, green or blue.

Suitably secured to the base is an indicator 20 body portion 20 and projecting transversely thereof on opposite sides, are the several indicators or pointers 21, each being spaced from the adjacent indicator and each terminating in a somewhat pointed end 22, which, as shown clearly 25 in Fig. 1, is emphasized by the portions 18 of the border.

The preferred form of the indicator in its 30 entirety is as shown in Fig. 3, since this type of an arrangement permits a strip of flexible material, such as light celluloid, or the like, from the roll to be passed through a rotary die, the width of the roll being substantially the length 35 of the indicator so that the rotary die will cut from the strips in succession without wastage of material, successive indicator units. It will also be noted that the base and cover may be formed from a single blank, as illustrated in Fig. 3.

To facilitate ready manipulation, preferably 40 there is employed, although in certain instances the same may be omitted, a spacing means 23 which spaces the plane of the indicator from the plane of the base or back. Herein, one form of such spacing means includes an elongated strip 45 23 which is secured together with the indicator body to the base by means of the staples 24. It is not essential this spacing strip be coextensive with the length of the body. It is also conceivable that the base may have elevated from the main plane an embossed portion at predetermined points or substantially coextensive with the body portion 20 of the indicator and thus the indicator be secured directly to the base so that the plane 50 55

of the indicator is spaced from the plane of the base.

It is also to be observed—see Fig. 1—that the lower portion of the cover has an area available 5 for advertising purposes, all of which may be printed on the cover at the time the border and individual names of articles are printed thereon.

It will also be noted that the spacing between pointers is of considerable length so that the 10 pointers are relatively elongated and relatively flexible, and there is sufficient length of spacing for any pointer to be engaged by the finger nail and flipped from behind the cover to lie in front of the cover, as shown to the right in Fig. 4.

15 To return the indicators, all that is necessary is to move the cover or the base relative to the other and preferably by elevating the cover which simultaneously will permit each of the flipped pointers to flex and pass through the aperture 16 20 and lie in the normal plane of the remainder 25 of the pointers and behind the cover when the cover is released.

It is not essential that the cover and the base be made integral. They may be made of two 25 pieces and hingedly connected together by a tape hinge substantially coincident with the connection 12 in the preferred embodiment illustrated, or in place of the latter modification or the preferred form, the cover and the back may be made 30 separate and the two eyeleted together substantially at the position indicated by the aperture 15. This then will permit the cover to be tilted relative to the base for simultaneous returning of the tripped indicators to non-indicating position. 35

In Fig. 5 there is illustrated a modified form of the invention somewhat of the general character herein before suggested and similar figures indicate similar parts. For example, 110 indicates the back and 111 the cover. The latter is apertured as at 116. The two separate members, to wit, cover and back, are united together by the eyelet 112 which provides an opening 115 for support of the entire structure upon a nail, 40 tack, or the like.

The body portion 120 of the indicators having the indicators 121 thereon, terminating in the pointed ends 122 spaced apart, as illustrated more clearly in Figs. 1 and 3, is suitably secured as by 50 the stapling 124 to the back 110 and if desired, there may be interposed therebetween the spacing member 123. In the simplest form, however, such spacing member is preferably omitted. This 55 form of the invention differs from that illustrated in Fig. 1 in that the back is provided with two elongated apertures 150 which are parallel and register, as it were, with portions of the pointers or indicators and aperture 116.

This device, it will be apparent, is capable of 60 dual indication, to wit, the front of the device may be arranged as illustrated in Fig. 1 and operate accordingly. If the entire device is turned so that the back is exposed, the latter may have printed on it other data or legend and in that 65 event, the indicators 122 may be moved in an opposite direction so that the free end or ends overlie the back and indicate merchandise to be purchased. In this way the device is a dual purpose indicator.

70 It is to be observed, however, that in so doing, the indicators cannot be automatically and simultaneously returned by relative movement between the cover and the back. In other words, each indicator will have to be independently returned. 75 However, with reference to the indicators which

are moved into indicating position relative to the cover legending, relative movement between the cover and the back will simultaneously return all indicators to the original non-indicating position. 5

While the invention has been set forth in considerable detail herein, such detailed disclosure is to be considered as illustrative and not restrictive in character. The modifications herein before mentioned, as well as others which will readily suggest themselves to persons skilled in this art, are all considered to be within the broad scope of this invention, reference being had to the appended claims. 10

The invention claimed is:

1. An indicator device including a cover member having an aperture therein, said cover having a plurality of independent legendings thereon in juxtaposition to the aperture, a plurality of flexible relatively independent and elongated pointers normally positioned such that the free 20 ends thereof lie behind the cover adjacent the aperture and manually movable into legend designating position by passing said free end through the aperture to overlie the cover, and a base member for supporting said pointers, one of said members being adapted for movement relative to the other to automatically return each pointer from indicating to non-indicating position in said relative movement. 25

2. An indicator device including a cover member having an aperture therein, said cover having a plurality of independent legendings thereon in juxtaposition to the aperture, a plurality of flexible relatively independent and elongated pointers normally positioned such that the free 30 ends thereof lie behind the cover adjacent the aperture and manually movable into legend designating position by passing said free end through the aperture to overlie the cover, a base member for supporting said pointers, one of said members being adapted for movement relative to the other to automatically return each pointer from indicating to non-indicating position in said relative movement, and means spacing said pointers from the plane of said base for the 35 purpose set forth. 40

3. An indicator device including a cover member having an aperture therein, said cover having a plurality of independent legendings thereon in juxtaposition to the aperture, a plurality of flexible relatively independent and elongated pointers normally positioned such that the free 45 ends thereof lie behind the cover adjacent the aperture and manually movable into legend designating position by passing said free end through the aperture to overlie the cover, and a base member for supporting said pointers, one of said members being adapted for movement relative to the other to automatically return each pointer from indicating to non-indicating position in said relative movement, and means spacing said pointers from the plane of said base for the 50 purpose set forth. 55

4. A device as defined by claim 3, characterized by the aperture exposed portion of the 55 spaced pointers being of appreciable width and length for finger engagement. 60

5. An indicator device including a cover member having an aperture therein, said cover having a plurality of independent legendings thereon in juxtaposition to the aperture, a plurality of flexible relatively independent and elongated pointers normally positioned such that the free 70 ends thereof lie behind the cover adjacent the aperture and manually movable into legend des- 75

- ignating position by passing said free end through the aperture to overlie the cover, a base member for supporting said pointers, one of said members being adapted for movement relative to the other to automatically return each pointer from indicating to non-indicating position in said relative movement, and means spacing said pointers from the plane of said base for the purpose set forth, said pointers all having a common body portion secured to the base, the apertured exposed portion of the spaced pointers being of appreciable width and length for finger engagement. 5
6. An indicator device including a cover member having an aperture therein, said cover having a plurality of independent legendings thereon in juxtaposition to the aperture, a plurality of flexible relatively independent and elongated pointers normally positioned such that the free 10 ends thereof lie behind the cover adjacent the aperture and manually movable into legend designating position by passing said free end through the aperture to overlie the cover, and a base member for supporting said pointers, one of said 15 members being adapted for movement relative to the other to automatically return each pointer from indicating to non-indicating position in said relative movement, said base and cover members being operatively connected together, 20 such connection permitting the aforesaid relative movement. 25
7. An indicator device including a cover member having an aperture therein, said cover having a plurality of independent legendings thereon in juxtaposition to the aperture, a plurality of flexible relatively independent and elongated 30 pointers normally positioned such that the free ends thereof lie behind the cover adjacent the aperture and manually movable into legend designating position by passing said free end through the aperture to overlie the cover, and a base member, one of said members being adapted for movement relative to the other for automatic return of each pointer to non-indicating position from 35 indicating position upon the cover, said second member including an aperture registering with the cover member and permitting manual movement of the pointers into indicating position relative thereto by passing the free end of the pointer through the second mentioned aperture, and legending on the face of said second member opposite the pointers for designation by the 40 pointers. 45
8. An indicator device including a cover member having an aperture therein, said cover having a plurality of independent legendings thereon in juxtaposition to the aperture, a plurality of flexible relatively independent and elongated pointers normally positioned such that the free ends 45
- 50
- 55
- thereof lie behind the cover adjacent the aperture and manually movable into legend designating position by passing said free end through the aperture to overlie the cover, a base member for supporting said pointers, one of said members being adapted for movement relative to the other to automatically return each pointer from indicating to non-indicating position in said relative movement, means spacing said pointers from the plane of said base for the purpose set forth, said pointers all having a common body portion, and means extending through said spacing means, body portion and base member for anchorage purposes. 5
9. An indicator device including a cover member having an aperture therein, said cover having a plurality of independent legendings thereon in juxtaposition to the aperture, a plurality of flexible relatively independent and elongated pointers normally positioned such that the free ends thereof lie behind the cover adjacent the aperture and manually movable into legend designating position by passing said free end through the aperture to overlie the cover, another member, one of said members being adapted for movement relative to the other for automatic return of each pointer to non-indicating position from indicating position upon the cover, said second member including an aperture registering with the cover member and permitting manual movement of the pointers into indicating position relative thereto by passing the free end of the pointer through the second mentioned aperture, and legending on the face of said second member opposite the pointers for designation by the 30 pointers. 35
10. An indicator device including a cover member having an aperture therein, said cover having a plurality of independent legendings thereon in juxtaposition to the aperture, a plurality of flexible relatively independent and elongated pointers normally positioned such that the free ends thereof lie behind the cover adjacent the aperture and manually movable into legend designating position by passing said free end through the aperture to overlie the cover, another member, said second member including an aperture registering with the cover member and permitting manual movement of the pointers into indicating position relative thereto by passing the free end of the pointer through the second mentioned aperture, and other legending on the face of said second member opposite the pointers for designation by the pointers. 40 45
